UNITED STATES PATENT OFFICE.

ANTON DVORAK, OF BERWYN, ILLINOIS, ASSIGNOR TO BEARDSLEE CHANDELIER MANUFACTURING COMPANY, OF CHICAGO, ILLINOIS, A CORPORATION OF DELAWARE.

DESIGN FOR A LIGHTING FIXTURE.

Application filed April 22, 1926. Serial No. 17,387. Term of patent 7 years.

To all whom it may concern:

Be it known that I, ANTON DVORAK, a citizen of the United States, residing at Berwyn, in the county of Cook and State of Illinois, have invented a new, original, and ornamental Design for Lighting Fixtures, of which the following is a specification, reference being had to the accompanying drawing, which forms a part hereof. The figure is an elevation of a lighting fixture showing my new design.

I claim:

The ornamental design for a lighting fixture as shown.

ANTON DVORAK.
